UNITED STATES PATENT OFFICE.

LOUIS WIDMAYER, OF CHICAGO, ILLINOIS.

POOL-RACK.

SPECIFICATION forming part of Letters Patent No. 294,422, dated March 4, 1884.

Application filed January 30, 1884. (No model.)

To all whom it may concern:

Be it known that I, LOUIS WIDMAYER, a citizen of the United States of America, residing at Chicago, in the county of Cook and State of Illinois, have invented certain new and useful Improvements in Pool-Racks, of which the following is a specification, reference being had therein to the accompanying drawings.

My invention relates to an improved pool-ball rack.

The object of the invention is to provide means for removing all the balls from the rack simultaneously, and, further, to provide means for locking the balls within the rack, to prevent their removal when not being used by players.

To the accomplishment of the above the invention consists of the novel devices and combination of devices as will be described and claimed.

Reference will be made to the accompanying drawings, in which Figure 1 is a front elevation of the rack; Fig. 2, a section on line 1 1 of Fig. 1; Fig. 3, a section on line 2 2 of Fig. 1, and Fig. 4 a section on line 3 3 of Fig. 1.

Like letters refer to like parts in each view.

The rack I prefer to make of iron, being cast in one or more pieces, as desired, and consisting of upright end pieces, *a*, and cross-pieces *b*. In one of the uprights a series of holes, *c*, are formed, one above the other, and of sufficient size to allow of the balls being passed therethrough, and the cross-pieces are sufficiently far apart to allow the players to distinguish the numbers generally marked thereon, but not to allow of the withdrawal of the balls from between them.

Cast upon the inner face of each upright *a* are a series of brackets or supports, *d*, situated as shown, and upon each pair of which a wooden cross-piece, *e*, is placed, said cross-pieces serving to divide the rack into compartments for the reception of the balls of separate players. At points near the top and bottom of the rack, and extending entirely across the same, are rods *f*, held in place by nuts *g*, or otherwise. These bars are passed through openings made near the top and bottom of a rod, *h*, which is free to move across the rack, and which, by the arrangement described, is guided on the rods *f*. Secured to the frame-

work at any suitable point, and extending thereacross, is a rod, *i*, which fits into a groove formed in a projection, *k*, of rod *h*, Fig. 2, said projection serving as a handle to rod *h*, by means of which it is conveniently moved. Cast with rod *h*, and at right angles thereto, so as to extend over the wooden cross-pieces *e*, are arms *l*. (Shown in Fig. 2.) These arms are so arranged that one of such will contact with the balls placed on each one of the wooden cross-pieces *e*.

The manner of using this part of the invention is as follows: The rod *h* is moved to the opposite end of the rack to that where the balls are inserted, and when it is desired to remove the balls from the several compartments simultaneously, said rod is moved along on its guides, the arms *l* thus being brought into contact with said balls and forcing them through the openings *c*, referred to, into any suitable basket or other receptacle.

The second part of the invention relates to the locking mechanism, or the means employed for preventing the removal of the balls, if desired, and consists of the following features: At points near the top and bottom of the upright *a*, through the openings *c* of which the balls are inserted, and near to the rear edge thereof, are formed brackets *m*, in which a rod, *o*, has bearings. Rod *o* has cast with it a series of arms, *p*, one for each opening *c*, and by turning said rod the arms *p* either close said openings or are carried away from them—in the first instance to prevent the withdrawal of the balls, and in the second to allow of the insertion or withdrawal of the same. One of the arms *p* is provided with an enlarged and hollow end, *q*, into which the catch of a spring-lock, *r*, enters when the arms are turned to close the openings. Lock *r* is secured to the upright *a*, and may be of any desired construction and operated by any suitable key, *s*.

By the arrangement of parts as last described, efficient means are obtained to prevent the removal of balls when desired.

If desired, the lock *r* may be other than a spring-lock, and a suitable spring, *h*, passed around rod *o*, to keep the openings always closed but not locked.

What I claim is—

1. A pool-rack formed of iron, and provided

with removable wooden cross-pieces or ball-supports, as described.

2. The combination, with a pool-rack, of a vertical rod provided with a series of arms, and adapted to force all the balls from the rack simultaneously, as described.

3. The combination, with a pool-rack, of a rod provided with arms adapted to close the orifices of said rack, and means for locking the parts together, as described.

4. The combination, with a pool-rack con-

structed as described, of a spring-lock, *r*, and a rod, *o*, provided with arms *p*, one of which is formed with an enlarged hollow end, *q*, as described.

In testimony whereof I affix my signature in presence of two witnesses.

LOUIS WIDMAYER.
